HOLE PUNCH OR SIMILAR ARTICLE

Herbert W. Marano, Brooklyn, N. Y., assignor to Wilson-Jones Company, Chicago, Ill., a corporation of Massachusetts

Application October 9, 1952, Serial No. 21,768

Term of patent 14 years

(Cl. D74—1)

To all whom it may concern:

Be it known that I, Herbert W. Marano, a citizen of the United States and a resident of Brooklyn, New York, have invented a new, original, and ornamental Design for a Hole Punch or Similar Article, of which the following is a specification, reference being had to the accompanying drawing, forming a part hereof, in which Figure 1 is a side elevational view of a hole punch or similar article, showing my new design; Figure 2 is a top plan view thereof; Figure 3 is a front elevational view thereof; and Figure 4 is a rear elevational view thereof.

I claim:

The ornamental design for a hole punch or similar article, as shown.
